UNITED STATES PATENT OFFICE.

LEON GSCHWIND, OF YOUNGSTOWN, OHIO, ASSIGNOR TO THE
YOUNGSTOWN FURNACE COMPANY.

GRATE.

No. 815,160.

Specification of Letters Patent. Patented March 13, 1906.

Application filed November 29, 1904. Serial No. 234,691.

To all whom it may concern:

Be it known that I, LEON GSCHWIND, a citizen of the United States, residing at Youngstown, in the county of Mahoning and State of Ohio, have invented certain new and useful 5 Improvements in Grates, of which the following is a specification.

My invention relates to improvements in grates, and refers particularly to a combined 10 rotary and dumping grate for use in stoves and furnaces.

One object of my invention is the provision of a grate which will be of the simplest, cheapest, and most durable construction, and 15 which can be operated with ease both for shaking and dumping, and which will be thoroughly efficient and entirely practical in every particular.

To attain the desired object, my invention 20 consists of a combined rotary and dumping grate embodying novel features of construction and combination of parts for service substantially as disclosed herein.

Figure 1 represents a top plan view of my 25 grate, with the parts of the grate in locked or closed position, as when the grate is in use. Fig. 2 represents a perspective view of the grate in open or dumping position, and Fig. 3 represents a sectional view on the line 3 3 of 30 Fig. 1.

In the drawings the letter A designates the main portion of the grate, which is substantially in the form of a ring or circle and provided with the openings B for the passage of 35 the ashes, and upon its periphery is formed with the socket or recess C, and upon its inner side opposite said recess is formed with the inward-extending grate portion D, having the lateral lugs or studs E, which form 40 bearings for the ears F, formed on the straight edge G of the inner substantially circular hinged grate-section H.

From this construction it will be observed 45 that my grate consists of the outer or ring section and the inner hinged or dumping section and the dumping-section is formed with the depending lugs J, arranged at the center and edge and which fit in the slot K of the shaking and dumping lever L, said lever hav-

ing the handle or grasping portion M, and the 50 intermediate fastening or securing tongue N, which in normal position engages the seat or recess C and serves to hold the hinged and outer sections in place in order that the operation of shaking can be properly performed, 55 and when desired to dump the grate it is simply necessary to pull the lever outward, which releases the tongue and the hinged section falls, dumping the grate of its entire contents. After the grate has been dumped it is 60 simply necessary to raise the lever and slide it inward to bring the parts into closed or locked position. Thus the grate by means of the single lever can be cleared by shaking or can be entirely rid of cinders and ashes by 65 simply dumping the hinged section and the parts instantly returned to operative position.

It will be observed that my grate comprises only three parts, thus insuring simplicity, durability, and inexpensiveness of 70 construction; also, that it can be operated with ease and will be thoroughly efficient, and that it can be assembled or taken apart by an unskilled person, and that it is practical in every respect.

I claim—

1. A grate composed of an outer member or section adapted to remain in a horizontal position under all conditions of operation, an inner dumping member or section and means 80 for connecting said members and for shaking both of said members and dumping the inner dumping member, said means consisting of a lever having an inner slotted end, slidably mounted on the dumping member and adapted to engage the outer or normally horizontal member to lock the dumping-section in its horizontal position.

2. A grate composed of an outer ring-section, a hinged or dumping inner section and 90 means for locking the sections together and for dumping said inner section or member, said means consisting of a lever having an inner slotted end, slidably mounted on the dumping inner section and adapted to engage 95 the outer or normally horizontal member to lock the dumping-section in its horizontal position.

3. A grate composed of a ring-section, a circular dumping-section hinged within said ring-section, and a sliding lever for locking the inner dumping-section and the ring-section together and for shaking said sections.

4. A grate composed of an outer section, a hinged inner section and a lever having a movable sliding connection with the hinged inner section for locking the sections together

and for connecting and rotating the sections to and dumping the hinged section.

In testimony whereof I affix my signature in presence of two witnesses.

LEON GSCHWIND.
